UNITED STATES PATENT OFFICE.

JAMES B. BLACKSHEAR, OF HONOLULU, TERRITORY OF HAWAII.

SINKABLE TOY SHIP.

1,292,422.

Specification of Letters Patent. Patented Jan. 28, 1919.

Application filed February 16, 1918. Serial No. 217,597.

To all whom it may concern:

Be it known that I, JAMES B. BLACKSHEAR, a citizen of the United States, and a resident of the city and county of Honolulu, 5 Territory of Hawaii, have invented a new and Improved Sinkable Toy Ship, of which the following is a full, clear, and exact description.

My invention relates to toy ships having 10 means whereby to cause submergence.

An object of the invention is to provide a toy ship adapted to be sunk by admitting water thereto, the inlet of water being controlled by displaceable valve means.

15 A further important object of the invention is to provide for release of the valve means by the hitting of a target which advantageously simulates a boat swung in supports generally suggestive of davits.

20 The invention also has for its object to provide a trigger engageable with the target and releasable to open the inlet valve and so arranged that the setting of the trigger permits the valve to automatically close for 25 maintaining the ship in floatable condition.

A more specific object of the invention with respect to the sinkable features of the ship is to increase the attractiveness of the toy by causing bubbles to rise through the 30 smoke stacks when the ship sinks.

The invention also has for its object to utilize in a novel manner the propelling power of a twisted rubber band or strand and to provide a rudder, the angular position of which is controlled by a novel and 35 simple means.

Reference is to be had to the accompanying drawings forming a part of this specification in which similar reference characters indicate corresponding parts in all the views, it being understood that the drawings are merely illustrative of one example of the invention.

Figure 1 is a longitudinal vertical section 45 of a toy ship embodying the invention;

Fig. 2 is an enlarged transverse vertical section taken in the main on the line 2—2, Fig. 1;

Fig. 3 is a fragmentary view given to 50 show the rudder controlling means;

Fig. 4 is a fragmentary view similar to Fig. 1 but showing a modification of the valve means and trigger.

In carrying out my invention in practice 55 a buoyant hull is provided, which may consist of a solid buoyant block 10 which in

practice is of wood and a superstructure in the form of a tank 11. On the block 10 is a metal keel 12 to give the desired submergence. The ship may in practice simulate a 60 warship or an armed merchant vessel, there being indicated a bow gun 13; the numeral 14 indicates a flagstaff.

The tank 11 has an inlet opening, or openings, 15, in the bottom thereof through 65 which water may enter and escape, and said inlet is controlled by a valve 16 Figs. 1 and 2 in the form of a plain disk valve beneath the tank, from which a stem 17 rises centrally through the bottom of the tank, said 70 stem within the tank being surrounded by a coil spring 18 abutting at its lower end against the bottom of the tank and at its upper end against the head or flange 19, whereby the tendency of the spring will be 75 to maintain the valve against the under side of the tank and closing the inlet or inlets 15. Above the valve stem is a trigger 20 generally in the form of a vertically movable plunger which extends water-tight through 80 the deck of the vessel as formed by the top of the tank 11. The upper end of the trigger 20, above the tank, has a lateral offset trigger arm 21 which engages the target 22 85 simulating a boat, said target having trunnions 22^a adapted to turn in standards 23 simulating or suggesting davits. One trunnion 22^a has a crank arm 24 to be engaged by the trigger arm 21. A coil spring 25 encircles the plunger 20 within the tank 11, 90 said spring abutting at its upper end against the top of the tank and abutting at its lower end against the flange or head 26 disposed directly above the head 19 of the valve.

With the described arrangement any suitable projectile discharged from a toy cannon or otherwise, and hitting the target 22, will rock the same on its trunnions, thereby releasing the trigger 20 and permitting the latter to be depressed by its spring 25, 95 which spring is of greater strength than the valve spring 18, so that the valve is depressed and the inlets 15 thereby opened. Any suitable arrangement may be provided for directing water to the inlets 15, there being shown in the illustrated example a transverse passage 10^a in the block 10 and said passage being open at its ends for the free inlet and escape of water. The valve 16 has clearance in a valve chamber or depression 10^b in the block 10. Obviously, 100 entrance of water in the tank 11 will gradually 105

cause the sinking of the vessel. When the vessel is raised after having been sunk, the pressure of the spring 25 will still maintain the valve 16 open, thereby permitting water 5 to drain from the tank 11 through the openings 15 and passage 10^a, after which the setting of the trigger 20 and its engagement with the target 22 will have relieved the valve stem 17 of the pressure of the spring 10 25, thereby permitting the valve to automatically close under the action of its spring 18.

A smoke stack or smoke stacks 27 on the tank 11 and communicating with the interior thereof results in bubbles escaping through the smoke stacks as the vessel continues to sink deeper in the water, after the complete submergence of the smoke stacks, the bubbling adding to the realism of the 20 sinking.

The illustrated propelling means includes a rubber band or strand 28 which ranges longitudinally of the vessel in a longitudinal bore 29 in the block 10. The rear end of the 25 propelling strand is secured to the shaft 31 of the propeller 30 which turns in a frame designated generally by the numeral 32. The front end of the propelling strand is secured to a suitable twisting device 33 at 30 the bow of the vessel. Said twisting device is shown as a crank spindle which has a comparatively tight fit in a bearing 33^a or otherwise being provided with suitable means to prevent too free a turning so that 35 the reaction of the strand 28 will be effective only on the propeller 30.

In the illustrated example the frame 32 is bent rearwardly at an incline and secured to the correspondingly inclined overhang of 40 the tank 11 at the stern, and the frame has a depending bearing member 32^a for the propeller shaft. The single frame 32 is also formed with members to support and control the rudder 39, said frame being carried 45 forwardly at the bottom as at 35 and then upwardly as at 36 and secured to the rear end of the block 10. From the upright member 36 the frame is carried rearwardly as at 37 to form an upper bearing member 50 which with the bottom 35 constitutes a bearing for the rudder spindle 38 on which the rudder 39 is hung. The upper arm 37 has a downward bend at 40, the lower edge of which is serrated as at 41 to yieldingly engage the upper edge of the rudder 39 for 55 holding the latter in a given angular adjustment. The said rudder 39 and the frame members of the frame 32 are sufficiently resilient to permit the manual adjustment of the rudder as desired.

In the form shown in Fig. 4 the parts are the same as in Fig. 1 except that the trigger 20^a carries the valve 16^a which is disposed above the openings 15 and a plate 60 spring 25^a secured at one end to the hull

10 and engaging at its free end the valve 16^a, serves to throw the valve to the closed position when the trigger 20^a is released. The trigger stem 20^a is held in depressed position to close the valve, by the crank arm 70 24 bearing on head 21^a. Inasmuch as the other features shown in Fig. 4 correspond with Fig. 1, the same identifying characters are employed.

If desired, a suitable device may be employed to temporarily hold the propeller 30 against turning while the elastic element 28 is being twisted. As shown for the purpose in Fig. 1 a pin 42 is slidable in the parts 80 32, 32^a whereby to be moved rearwardly between the blades of the propeller or shifted forwardly to disengage the propeller and leave the latter free to turn.

For the quick emptying of the tank, the water may be spilled through the smoke stacks instead of permitting it to slowly escape through the openings 15. If desired, the spindle 33 may be pinched as at 33^b to engage the roughened or toothed end of bearing 33^a to thus prevent backward turning of the spindle.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I 100 claim as new, and desire to secure by Letters Patent:

1. A sinkable toy ship including a tank having means for the inlet and escape of water, valve means controlling the admission of water to the tank, a target, and a trigger releasable by the target and adapted to positively actuate said valve means for admitting water to the tank to sink the ship when the target is struck.

2. A sinkable toy ship including a tank having a water inlet below the water line, a valve controlling the inlet, a spring-pressed trigger movable to open the valve, and a target engageable with the trigger to restrain the same, the target being movable for releasing the trigger and permitting the latter to open the water valve.

3. A sinkable toy ship having a water inlet below the water line, a spring-pressed valve for closing said inlet, a valve stem rising from the valve and extending above the deck of the vessel, and a rockable target engageable with said stem and movable when struck by a projectile to a position to release the stem and permit the valve to close.

4. In a toy ship, a frame on the stern thereof and presenting an approximately horizontal bottom member, the frame being

- carried upwardly from the front end of said horizontal member in the form of a securing member made fast to the ship, and then carried rearwardly and downwardly forming 5 an upper overhanging bearing member, and a depending free end, said free end having a serrated bottom edge, a rudder in said frame between the bottom member and overhanging member, and a rudder spindle having 10 bearings in said bottom and overhanging members, said serrated free edge being variously engageable with the top edge of the rudder.
5. In a toy ship, a frame on the stern 15 thereof and presenting an upright member, the frame at the upper end of said upright member being carried rearwardly and then downwardly to provide a securing member, and a depending free end constituting a 20 bearing member, a propeller turning in said upright and in said bearing member, said

frame being carried forwardly from the lower end of said upright in the form of an approximately horizontal member, then upwardly in the form of a securing member 25 made fast to the ship and then rearwardly and downwardly to present an upper overhanging member and a depending free end, said free end having a serrated bottom edge, and a rudder supported in said bottom and 30 overhanging members, the serrated free edge being variously engageable with the top edge of the rudder.

6. In a toy ship, a rudder mounted to be turned for varying its angular position, and 35 a rudder controlling member adjacent to the rudder and presenting a serrated edge adjacent to an edge of the rudder, said rudder and its said controlling member being relatively yieldable to variously engage the re- 40 spective adjacent edges.

JAMES B. BLACKSHEAR.
